UNITED STATES PATENT OFFICE.

JULIUS C. GOODWIN, OF PHILADELPHIA, PENNSYLVANIA.

BUTTONHOLE-SEWING MACHINE.

SPECIFICATION forming part of Letters Patent No. 606,204, dated June 28, 1898.

Application filed December 29, 1893. Serial No. 495,046. (No model.)

To all whom it may concern:

Be it known that I, JULIUS C. GOODWIN, of Philadelphia, in the county of Philadelphia and State of Pennsylvania, have invented certain new and useful Improvements in Button-hole-Stitching Machines, of which the following is a specification.

The object of the present invention is to stitch a straight buttonhole having two parallel sides and two bars extending across and joining the ends of the two sides by a continuous stitching operation and with any of the usual sewing-machine stitches, lock or chain.

15 The buttonhole-stitching machine equipped with the present improvements stitches first one straight side of the buttonhole, then a bar across one end, then the second straight side, then the second bar across the other end, the stitching terminating at the point where it commenced, and finally cuts the buttonhole-slit, the entire operation from the initial stitch to and including the cutting of the slit being continuous and wholly automatic.

The present improved machine accomplishes the desired result and performs the indicated operation by a number of coöperating groups of instrumentalities.

30 The machine includes, first, stitching mechanism comprising a needle above the work and a shuttle or loop-taker beneath the same, similar to the corresponding parts of an ordinary family or other sewing-machine, except that the needle-bar has a vibratory as well as a rectilinearly-reciprocating movement, the vibratory movement determining the bight of the stitches; second, work clamping and feeding mechanism which feeds the work back and forth in the direction of the length of the buttonhole while the straight sides of the buttonhole are being stitched and which feeds the work to and fro at right angles to the general direction of the feed while the bars are being stitched; third, cutting mechanism for cutting the buttonhole-slit after the stitching has been completed; fourth, stopping mechanism for automatically stopping the machine when a buttonhole is completed; 45 and for enabling the machine to be stopped at any time at the will of the operator; fifth, tension-release mechanism whereby the ten-

sion on the thread is automatically released when the work is to be moved for stitching a new buttonhole or for other purposes; sixth, 55 quick-motion mechanism enabling the work to be fed rapidly by hand to any desired position—as, for example, when the thread has broken—and, seventh, adjusting mechanism for regulating the length of the buttonhole, 60 the bight of each stitch, the number of stitches per inch, and the distance between the two straight sides of the buttonhole.

The present invention consists in the improved construction of these several groups 65 of instrumentalities and their relative coöperative arrangement.

For the purposes of illustrating and specifically describing the present improvements I have selected for illustration the application 70 of the improvements to a sewing-machine having the general characteristics of the well-known "Standard" family sewing-machine.

In the accompanying drawings of the invention so applied, Figure 1 is a side view of 75 the improved machine. Fig. 2 is a plan view, the front portion of the overhanging arm being removed. Fig. 3 is a front view, the face-plate being removed. Figs. 4, 5, and 6 are detail perspective views of the work-clamp. 80 Fig. 7 is a diagrammatic view illustrating the operation of the needle. Fig. 8 is a view looking toward the rear or inner face of the needle-bracket and illustrating the mechanism for oscillating the needle-bar laterally. 85 Fig. 9 is a central vertical section of the parts shown in Fig. 8. Figs. 10, 11, and 12 are detail views of the adjusting means for changing the bight of the stitches. Fig. 13 is a detail view of a special cam employed. Fig. 14 is a view, partly in section, looking toward the front side of the standard and illustrating the initial operating mechanism for feeding the work. Fig. 15 is a central vertical section of the principal parts illustrated in Fig. 14. Fig. 16 is a plan view of the disk which carries the mechanism employed for converting uniform circular movement into uniform reciprocating movement. Fig. 17 is a vertical section of 90 the parts shown in Fig. 16, the cam-stud being also shown in place. Fig. 18 is a detail vertical section of the connections between the work-carrier and the lever which imme-

diately operates it. Fig. 19 is a detail plan view of the mechanism for feeding the work laterally during the formation of the bars. Fig. 20 illustrates parts in detail of the same mechanism. Figs. 21, 22, 23, and 24 are diagrams illustrating the portions of the feeding mechanism which convert uniform circular motion into uniform reciprocating movement. Fig. 25 is a detail front view of the cutting mechanism. Fig. 26 is an underneath view of the operating mechanism for the cutting mechanism. Fig. 27 is a partly-diagrammatic rear view of the machine, partly in section, illustrating the stop-motion. Figs. 28 and 29 are detail views of portions of the stopping mechanism. Figs. 30 and 31 are detail views of the tension-release. Fig. 32 is a view of the completed buttonhole. Fig. 33 is a diagram illustrating the formation of the buttonhole.

Figs. 1, 2, 3, 14, 15, 27, 30, and 31 are drawn to a standard scale indicated on Sheet 1. Figs. 7, 32, and 33 are not drawn to a scale. Figs. 21, 22, 23, and 24 are drawn to a scale three times as large as the standard scale. The remaining figures are drawn to a scale one and a half times as large as the standard scale.

A is the bed-plate of the machine, upon which all of the other parts are mounted. B is the upright hollow standard. C is the overhanging arm. D is the needle-bracket. E is the main horizontal drive-shaft. F is the drive-pulley on the main shaft, and G is the rotary loop-taker or shuttle-shaft located beneath the bed-plate, which receives rotary motion from the main shaft by well-known intervening mechanism located within the standard B, which is not illustrated because well known. All of these parts, except as hereinafter specified, are or may be of any well-known construction—such as, for example, that of the "Standard" sewing-machine.

The stitch-forming mechanism.—The shuttle or loop-taker is carried on the front end of the shuttle-shaft G, and since it possesses no novelty and since any known loop-taker or shuttle mechanism may be employed it is not shown. The needle a is carried by a needle-bar H, which is given a vertical rectilinear reciprocation in the usual manner by a link b, connected to a crank-pin c upon a disk at the front end of the main shaft E. In addition to this rectilinear movement the needle-bar has a lateral vibratory movement—that is to say, it swings back and forth in a vertical plane which is at right angles to the axis of the shaft E. The aperture in the top of the needle-bracket, through which the upper end of the needle projects, is sufficiently large to permit the lateral vibration of the needle-bar. This lateral vibration is so timed that the needle passes through the work and through the eye d in the bed-plate at a given point at one descent, and then at the next succeeding descent of the needle-bar

the needle passes through the work and the eye d at a different point, the eye d being elongated for this purpose. This movement of the needle is indicated in Fig. 7, wherein 70 d is the elongated eye, and a' a² are the two positions in which the needle passes alternately through the eye. The distance between these two positions a' a² determines the bight of each stitch at the buttonhole. 75

The mechanism for laterally vibrating the needle-bar is as follows: I is a short shaft parallel with and directly beneath the front end of the main shaft, Figs. 1, 8, and 9. This shaft has on its rear end a pinion e, which 80 meshes directly with a pinion f on the main shaft, having half the number of cogs, so that the shaft I is rotated once for each two rotations of the main shaft. On its front end the shaft I carries a two-cornered cam J, (see Fig. 8,) which occupies an open slot or fork g in the upper end of a lever K, which at its lower end is pivoted by means of a pivot-stud h to suitable devices, hereinafter more particularly described, carried by the bracket D. 90 The needle-bar passes through an oscillating collar L, Fig. 9, to which is rigidly secured a pintle i, which is free to rock or oscillate in a sleeve M. This sleeve is connected by a groove j and pin k with a slide N, which 95 slides rectilinearly in a horizontal path at right angles to the axis of the main shaft E in suitable guides formed in the rear of the bracket D and by guide-screws l. Immediately back of the slide N, encircling the sleeve 100 M, is an annular bearing-ring m, which is located in a circular aperture in the lever K. At its extreme rear end the sleeve M is screw-threaded to receive a retaining-nut n. At each revolution of the auxiliary shaft I the 105 lever K is oscillated back and forth on its pivot h. As the lever thus moves back and forth laterally it carries with it the sleeve M, slide N, collar L, and consequently the needle-bar H. The collar L, since its pintle 110 rocks within the sleeve M, compensates for the oscillation of the needle-bar, which swings through a minute arc on the pivot between it and the link b. The function of the sleeve M is thus to form a bearing for the collar L and 115 also to connect the lever K with the slide N and the collar L. The two-cornered cam J gives a complete oscillation to the lever K at each revolution of the shaft I. The cam has (see Fig. 13) a major dwell 21 and a minor dwell 120 22 at different radial distances from the axis, and these are connected by two abrupt inclines or corners 23 23. Consequently the oscillation in either direction imparted by the corners 23 is quickly effected. By means of 125 the cam J the oscillation of lever K and consequently the lateral vibrations of the needle-bar occur when the needle is out of the work. Since the main shaft E rotates twice as fast as the auxiliary shaft I, the needle-bar is 130 moved in one direction during one of its complete rectilinear reciprocations and is moved

in the opposite direction during the next rectilinear reciprocation, and in this manner the desired results indicated in Fig. 7 are effected.

Work-clamping mechanism. (see Figs. 2, 4, 5, and 6.)—The work-clamp is mounted on a carrier O and consists of two jaws P and Q. The lower jaw P is rigidly connected with the carrier O and rests directly on the upper surface of the bed-plate A. The lower jaw is a flat plate having a central rectangular slot n' longer than the longest buttonhole to be made and wider than the extreme width of the widest buttonhole and its stitches. The upper jaw Q is a rectangular frame having serrations or teeth on the lower edges of its longitudinal bars and having a central rectangular opening o longer and wider than the longest and widest buttonhole to be made, including its stitches. The lower clamping edges of the upper jaw are wholly within the slot n' of the lower jaw, so that when no work is in place the clamping edges of the upper jaw come in contact with the upper face of the bed-plate. The upper jaw is supported as follows: R is a bracket rigidly secured to the work-clamp carrier O, and it has at its upper outer end a forwardly-projecting pintle p. Upon this pintle a rocking frame S is journaled so as to swing up and down. This frame has on its inner end a boss or stud q, upon which is journaled a fork T, which rocks up and down in a plane at right angles to the length of the frame S. The jaw Q is pivoted to and between the arms of the fork T by pivot-pins r r, which allow the jaw to swing thereon. The pivot-pins and stud r r and q constitute a universal or gimbal joint for the upper jaw, so that it can accommodate itself to irregularities in the work. The upper jaw Q is normally clamped and held firmly down upon the work by a flat spring U, secured at its rear end to the carrier O and bearing down at its front end upon a pin s upon the fork T immediately below the pivot-stud q. The tension of the spring U is regulated by a screw t. The pivoting-pintle p permits the jaw Q to rise and fall to accommodate itself to different thicknesses of material and at the same time allows the rocking frame S to be swung upwardly, so as to lift the jaw Q entirely free from the work in order to enable the work to be inserted, removed, or shifted from one buttonhole to the next. The rocking frame S has a manipulating-handle V, which can be operated by hand, but which is preferably connected with a treadle, so that it may be worked by foot, thus leaving both hands of the operator free to manipulate the work. The work is placed upon the lower jaw P when the upper jaw Q is elevated. When the upper jaw then descends, the work is firmly clamped between the two jaws.

Work-feeding mechanism. — The work-clamp carrier, or, for brevity, the work-carrier O, has two movements, one a step-by-step lengthwise back-and-forth movement in

the direction of the axis of the drive-shaft E and of the length of the slots n' in the clamp-jaws and at right angles to the lateral vibration of the needle, and the other a step-by-step lateral to-and-fro movement at right angles thereto. The operation of the work-carrier and its co-operation with the needle will be readily understood by reference to the diagram Fig. 33. When the buttonhole is to be commenced, the carrier occupies its position nearest the standard B. The first stitch made is the stitch w' , which is formed by the needle first entering the cloth at the point in the line 24 24 and then at its next descent at the point in the line 25 25. The carrier then moves forward a step, carrying with it the cloth, so that at the next two descents of the needle the stitch w^2 is formed, and so on until the first straight side w (see Fig. 32) is completed, the travel of the cloth being indicated by the arrow 26. When the first straight side is completed, the longitudinal movement of the carrier ceases and its lateral step-by-step movement commences in the direction of arrow 27. During the lateral movement of the carrier, since the needle maintains its regular movement, the successive bar-stitches $x' x^3$ are formed overlying each other and constituting the first bar x . (See Fig. 32.) The lateral movement of the carrier then ceases and it commences its second longitudinal movement in a backward direction opposite to the first or forward direction. The last bar-stitch x^3 constitutes the first stitch of the second straight side y , which is formed in exactly the same manner as the first straight side, except that the work is fed in the opposite direction. When the carrier has moved backward exactly as far as it moved forward, its backward longitudinal movement ceases, and it then moves laterally in a direction opposite to its first lateral movement. During this second lateral movement the second bar z is formed, the last stitch overlying the initial stitch w' . The last stitch is formed just as the carrier reaches its original position, and immediately thereafter, as will be hereinafter explained, the machine stops automatically. The stitching is in fact zigzag stitching, but the connecting-stitches have not been indicated in diagram Fig. 33, since they would tend to confuse the same. The zigzag character is indicated, however, in Fig. 32. It will be noted that all of the stitches in both sides and in the bars are just alike.

The longitudinal and lateral movements of the work-carrier are effected in the following manner: The carrier O has a bottom plate W, provided with guide-flanges u u, between which the carrier slides back and forth. The plate W itself slides laterally on the bed-plate A, suitable devices, such as studs v v, secured to the bed-plate and entering slots in the plate W, guiding the same. The initial work-carrier-operating instrumentality is a two-cornered cam X (similar to the cam J) on the main shaft E, (see Fig. 14,) which occu-

plies an open slot or fork 28 in the upper end of a vertical lever Y, which is pivoted by a pivot-pin 29 near its middle to the standard B. The lower end of this lever Y is connected by 5 a horizontal pivot-pin 30 to a link 31, which is connected by a vertical pivot-pin 32 to a second link 33, which in turn is connected by a vertical pivot-pin 34 to a horizontally-swinging pawl-lever Z, which lies flat on the bed-plate A and is pivoted thereto by a vertical pivot 35. (See Fig. 2.) Midway between its two pivots 34 35 the pawl-lever carries a spring-pressed pawl 36, which engages a horizontally-disposed ratchet-wheel 37, (see Fig. 1,) which lies flat just above the bed-plate A and which rotates on a vertical stud 38, (see Fig. 17,) fixed to the bed-plate. The ratchet-wheel is turned step by step in the same direction, (indicated by the arrow 39, Fig. 2,) 10 and is prevented from backward rotation by a spring-detent 40, Fig. 1. Rigid with the ratchet-wheel, Fig. 17, is a disk 41, which carries on its upper face an eccentrically and fixedly located three-cornered cam-stud 42, so that as the disk rotates the cam-stud travels in a circular path. This cam-stud enters the elongated slot 43 of a slotted yoke 44, having a straight stem 45, sliding longitudinally in guide-apertures of a fixed guide-bracket 46. 15 This yoke 44 is connected by a horizontally-swinging link 47 to the outer end of a lever 48, which swings horizontally on a fixed vertical stud 49 on the bed-plate. The inner end of this lever is connected with the work-carrier O, which has a vertical pin 50, (see Fig. 18,) around which is a sleeve 51, upon which turns a block 52, sliding in a rectangular slot 53 in the lever 48, whereby a connection is provided which accommodates the swinging 20 movement of the lever to the rectilinear and lateral movements of the carrier. The disk 41 has at its periphery cog-teeth, converting it into a gear, and it meshes with an idle-pinion 54, which turns on a fixed vertical stud 55 on the bed-plate. (See Fig. 19.) 25 The hub 56 of the pinion 54 serves as the fulcrum-stud of a swinging plate 57, which is connected with the laterally-sliding plate W of the work-carrier by a link 58. The plate 57 has also a rectangular aperture 59, through which extends a vertical stud 60, fixed to the bed-plate A, upon which turns a gear-wheel 61, meshing with the pinion 54. Fast to the under side of the gear 61 is a two-cornered cam 62, (similar to the cam J,) having dwells 63 64 and inclines or corners 65 66, said cam 62 fitting within the aperture 59 of the swinging plate 57. 30 The cam X on the main shaft swings the lever Y back and forth, thereby swinging the pawl-lever Z. The two links 31 33 constitute a gimbal or universal connection between the levers Y Z, compensating for the arcs in different planes in which they swing. The pawl 66 moves the disk 41 intermittently in the same direction, thereby causing the cam-stud 42 to travel in a circular path. This inter-

mittent circular movement imparts an intermittent rectilinear movement first forward and then back to the yoke 44 by reason of the elongation of its slot 43. The intermittent forward and back movements of the yoke 44 are transmitted to the carrier O by the link 47 and lever 48. Since the intermittent or step-by-step movement of the carrier is thus received from a cam on the main shaft which drives the needle-bar, the movements can be timed so as to occur when the needle is out of the work by properly positioning the cam X on the main shaft relatively to the location of the crank-pin c, which drives the needle-bar. While the work-carrier is thus being operated, the gear 61 is being given a step-by-step rotation, thus turning its cam 62 within the aperture 59 of the plate 57. While the work-carrier is being moved forward under the influence of the cam-stud 42 and the first straight side of the buttonhole is being stitched, the major dwell 63 has been in contact with the outer margin 67 of said aperture, thereby maintaining the bottom plate W and with it the carrier O in their position nearest the front (regarding the part of the machine at which the gear 61 is located as the "front") of the machine. When, however, the carrier 95 reaches the forward limit of its motion, the cam 62 has so far turned as to bring the cam rise or corner 65 into co-operative relation with the inner margin 68 of the slot 59, whereupon the plate 57 is swung inwardly and the work-carrier is moved laterally and the first bar is stitched. Then while the major dwell 63 is in contact with the inner margin 68 of the slot 59 the work-carrier remains in its inward position, during which period the second 100 straight side of the buttonhole is stitched. When, however, the second straight side is completed, the cam-rise 65 is brought into co-operative relation with the outer margin 67 of the slot 59, whereupon the plate 57 and 105 work-carrier O are restored to their original positions.

Since the rotary motion of the cam 62 is derived from the disk 41, which has a uniform rotary motion, and since the cam-stud 42 on said disk is likewise a uniformly-rotating stud, it would follow if the stud were simply a circular stud within the slotted yoke 43 that not only would the longitudinal feed of the work continue during the formation of the 110 bars, but also the stitches of the straight sides of the buttonhole would be unequally spaced, since the successive steps of the longitudinal progression of the yoke, and hence of the work-carrier, would vary proportionately to 115 the difference in the lengths of the sides of the successive arcs through which the stud travels. To properly form the side and bar stitches of the buttonhole, it is hence necessary not only that the uniform rotary movement of the disk 41 should be converted into uniform reciprocatory movement for the work-carrier, but also that the reciprocation 120 of the carrier shall wholly cease during the 125

lateral movement of the carrier while the bars are being formed. These results are achieved in an exceedingly simple manner by the shape of the cam-stud 42. This stud is 5 not circular in outline, but is cam-shaped, as is best shown in diagram Figs. 21 to 24. The cam-stud has an apex 69, two heels 71 and 73, and three curved sides 70, 72, and 74 therebetween. The apex 69 is at the point 10 most remote from the axis 38 of the disk 41. The curved side 72 is nearest to the axis 38 and at its tangential point is at right angles to the axis. The heels 71 and 73 are at equal 15 distances on opposite sides of the radial line intersecting the apex and axis. The outline of the cam-stud is hence approximately an isosceles triangle having rounded corners and sides, the sides being wholly within a circle tangential to the apex and heels.

20 Now it will be noted that while the cam-stud during one rotation of the disk 41 performs a revolution around the axis of the disk it also performs a rotation on its own axis within the slot of the yoke 44. The motion 25 of the cam-stud in this respect is similar to that of the moon in its revolution around the earth. The result is that during each complete revolution of the cam-stud its apex, heels, and curved sides each come in contact 30 successively with both margins 180 and 181 of the slot of the yoke 44.

Assume now as a starting-point that the cam-stud 42 occupies the position shown in Fig. 21, with the radial line intersecting its apex 35 and the axis 38 perpendicular to the line of reciprocation 182 182 of the yoke, and that the cam-stud is revolving in the direction of the arrow 39. If the cam-stud were truly circular, it would follow that in the position shown 40 in Fig. 21 the yoke would be given its maximum extent of movement; but with the improved cam-stud the extent of movement which would otherwise be produced by the revolution of the cam-stud is diminished by 45 reason of the circumstance that the cam-stud turns in the slot of the yoke, so that the forward curved side 70 rolls along the margin 180 of the yoke-slot. As the consequence of 50 this rolling motion the advance of the yoke is retarded by an amount equal to the departure of the side 70 from a circumscribed circle tangential to the apex and corners. When, however, the cam-stud in its revolution around the axis 38 passes the point where its 55 average travel is equal to the average (and constant) travel of the slotted yoke—that is to say, when the angle between the radial line intersecting the apex 69 and axis 38 (hereinafter called the "radius of the cam-stud") and the line 182 182 is less than sixty degrees—the cam-stud advances the slotted arm more rapidly than a circular stud would do, since as the side 70 approaches the apex it approaches the circumscribed circle, and when the advance of the slotted yoke due to the revolution of the cam-stud grows still less the loss is compensated, as indicated in Fig. 22, by

the apex itself coming in contact with the margin 180. As soon, however, as the cam-stud reaches the position shown in Fig. 23, 70 where its radius coincides with the line 182 182, not only does the outward travel of the slotted yoke wholly cease, but also the slotted yoke remains for a time wholly stationary. This is due to the fact that immediately after 75 passing the position of Fig. 23 the curved side 72 of the cam-stud rolls along the margin 181 of the yoke-slot without moving the yoke, and it is not until the forward heel 71 begins to act on the margin 181, as shown in Fig. 24, 80 that the reverse movement of the slotted yoke begins. It is during this quiescence of the yoke that the bar at one end of the button-hole is formed.

From the position shown in Fig. 24 around 85 in the direction of arrow 39 to the position shown in Fig. 21 the action is merely a repetition of the actions already described. It will be noted that the apex 69, forward curved side 70, forward heel 71, and curved side 72 90 are the operative parts of the cam-stud, the rear heel 73 and side 74 having merely the function of enabling the cam-stud to always fill the slot of the yoke and so prevent any loose play thereof.

Cutting mechanism.—Occupying the place in the needle-bar bracket D of the presser-bar of an ordinary sewing-machine is the movable cutter-carrier 75. This bar is mounted so as to be capable of vertical longitudinal reciprocation and is normally upheld by a spring 76. It is prevented from rotary movement by a square stud 77, working in a rectilinear way 78 in the bracket D. (See Figs. 30 and 31.) At the lower end of the 105 cutter-bar 75, below the bracket D, it carries a horizontal plate or cutter-carrier 79, fixed to it, said carrier being located to the rear of the needle-bar. Rigidly but removably connected to this plate is the knife or cutter 80, 110 (see Fig. 25,) which extends vertically and has a shear cutting edge in line with the buttonhole at an angle to the horizontal. Co-operating with this knife is a slit 81 (see Fig. 6) in the bed-plate adjacent to the plate-eye 115 d and extending rearwardly therefrom. Pivoted at 82 to the carrier 79 is a horizontally swinging lever or movable tappet 83, (see Fig. 2,) the forward end of which co-operates with a projecting stud or pin 84, carried by the 120 needle-bar H. When the tappet 83 is in its operative (but abnormal) position, it is located beneath but directly in the path of the stud 84, the tappet and stud thus constituting a coupling between the needle-bar and 125 the cutter-carrier, which is normally uncoupled, but which is coupled when the cutter is to become operative. Consequently when the parts of said coupling are coupled the needle-bar when it descends carries with it 130 the tappet 83, carrier 79, knife 80, and cutter-bar 75, thus causing the knife to descend through the slit 81, and thereby cutting the buttonhole-slit in the work. When the nee-

idle-bar again rises, the cutter is restored to its normal position by the spring 76. The machine is so timed that the knife descends only after the stitching is completed and when the work is in such position that the space between the two straight sides of the button-hole is directly beneath the knife. The cutter-operating tappet 83 consequently occupies its operative position momentarily only during the cutting of one buttonhole-slit and just long enough to permit the proper descent of the knife. The tail end of the tappet 83 has an elongated slot 85, Fig. 2, which is entered and occupied by a vertical operating-rod 86 long enough to coöperate with the tappet 83 during its up-and-down excursion. This rod extends through an elongated lateral slot 87 in the bed-plate and is connected rigidly beneath the bed-plate to a sliding bar 88, Figs. 3 and 26, which extends at right angles to the shuttle-shaft G and is adapted to slide laterally at right angles to said shaft G in suitable guides. This bar 88 is moved outwardly in the direction of arrow 89 for the purpose of moving the lever 83 into its operative abnormal position by a spring 90 and is moved in the opposite direction by a cam 91 on the shuttle-shaft G. The bar 88 is held in its normal position against the action of spring 90 by a trip-lever or movable trip 92, which is pivotally connected with the bed-plate. The lower end of this trip normally occupies a retaining-notch 93 in said bar and is held therein by a spring 94. This trip 92 extends through and above the bed-plate A in close proximity to the gear 61 and has a cam-incline 95 on its upper end. The cam-incline 95 is located in the path of a tappet 96, fixed to the gear 61 at such position as to insure the proper timing of its action. At the proper instant the tappet 96 encounters the cam-incline 95, thus swinging the trip 92 on its pivot and removing it from the notch 93 in bar 88. The bar is then instantly shifted by the quick action of spring 90, which is preferably a leaf-spring, with its free end bearing against a shoulder 97 on the bar 88. The bar is thus moved outwardly in the direction of arrow 89, carrying with it the rod 86 and the tail end of lever 83, thereby bringing the front end of said lever into the path of the stud 84 on the needle-bar. It is exceedingly important that the bar 88 should be shifted instantaneously to bring the lever 83 into operation, since the movement must be accomplished during the very brief interval while the stud 84 is above the lever 83. Before the needle-bar descends a second time the cam 91 on the shuttle-shaft G, which rotates at the same rate as the main shaft E, restores the parts to their normal inactive positions, the trip 92 automatically under the influence of its spring 94 catching in the retaining-notch 93 of the bar 88, the tappet 96 in the meanwhile having moved beyond and out of the way of the trip.

The action of the cutter, it will be noted, is wholly automatic.

Stopping mechanism.—Immediately after the knife has cut the buttonhole-slit and after it has been restored to its normal position and before the needle-bar again descends the machine is automatically stopped. The initiating instrumentality of the stop-motion is a stop-tappet 98 on the disk 41, (a location which enables the stopping to be accurately timed,) which at the proper instant comes in contact with the nose 99 (see Fig. 2) of a stop trip-lever 100, which extends horizontally to the rear and is pivoted at 101 to the bed-plate.

The drive-pulley F is loosely mounted on the main shaft E, and between said pulley and the standard B is a drum 102, fast to the drive-shaft. The drive-pulley F and drum 102 are operatively connected by a clutch comprising a fixed member 103 and a movable member 104. The fixed member 103 is a fixed stud on the inner face of the pulley F, from which it projects horizontally parallel with the shaft E at a radial distance from the axis of said shaft slightly greater than the radius of the drum 102. (See Figs. 3 and 27.) Consequently if the drum were not otherwise provided it would be entirely avoided by the stud 103, and consequently the pulley F would rotate freely on the shaft E without imparting any motion thereto. The movable clutch member 104 consists of a pawl which is pivoted at its tail end (see Fig. 27) by a horizontal pivot 105 in a recess 106 in the periphery of the drum 102.

When the pawl 104 is in its abnormal inactive position, it lies wholly within the recess 106, and its outer face is concentric with the axis of the drum 102, constituting a portion of the periphery of the drum, so that the stud 103 passes freely over it. The pawl, however, normally occupies an active position, with its free end projecting beyond the periphery of the drum in the path of the stud 103, so that the drum and with it the shaft E are rotated with the pulley F. The pawl is maintained in its outer active position by a coiled spring 107, located between it and the bottom of the recess 106, and the extent of its outward movement is limited by a link 108, pivoted to the pawl and having a slot 109, which is entered by a pin 110, fixed on the drum, the length of the slot 109 determining the extent of movement of the pawl.

In order to stop the motion of the machine, it is only necessary to push the pawl 104 inward out of the path of the stud 103 and to maintain it in such inward position. For this purpose the outer face of the pawl is provided with a depressed portion 111, (see Fig. 28,) which is flush with the periphery of the drum 102 when the pawl is in its projecting active position, and this depressed portion of its face terminates at the free end of the pawl in a cam-rise 112, which inclines from the portion 111 outwardly and terminates in a face 113 flush with the outer face of the pawl. The drum has a locking-notch 114 in its periphery communicating with the recess 106

and having one wall in the same plane with the wall of said recess opposite the free end of the pawl. The drum also has adjacent to the notch 114 a projecting stop-stud 115, the stop-face 116 of which is in a radial plane intersecting the axis of the shaft E and flush with the wall common to both the recess and notch—that is to say, the notch and recess both terminate at the stop 115 and at the free end of the pawl. The cam 112, notch 114, and stop 115 are all beyond the reach of the stud 103 on the pulley F.

Beneath the drum 102 is a horizontally-extending lever 117, pivoted to a horizontal stud 118 on the standard B and having near one end a stop-nose 119 and alongside thereof a tappet 120, both of which project toward the axis of the shaft E, the nose 119, however, projecting farther than the tappet 120. When the machine is to be stopped, the lever 117 occupies such a position that its nose 119 bears against the periphery of the drum 102, being pressed against the same by a spring 121. The rotating drum 102 being then rotated in the direction of arrow 122, the cam-rise 112 first encounters the tappet 120, which is then in its path, and thereby the pawl 104 is pressed inwardly out of the path of the stud 103 on pulley F, so that as the pulley continues its rotation its stud passes freely over the pawl 104. Immediately after the pawl has been thus depressed the notch 114 on the drum is brought into register with the locking-nose 119 on the lever 117, and the spring 121 forces the nose into the notch, thus holding the drum and the shaft E from further rotation. In case the speed and momentum of the drum should be so great as to endanger carrying the nose 119 over the notch 114 before the spring 121 has time to act the nose would encounter the stop-stud 115, thereby positively arresting the motion of the drum and insuring the dropping of the nose into the notch. While the nose 119 is in the notch 114, the tappet 120 bears against the elevated face or dwell 113 of the cam-rise 112, thereby holding the pawl 104 securely in the recess 106 out of the path of the stud on the pulley F.

The connection between the stop-lever 117 and stop trip-lever 100 is as follows: 123 is a lever pivoted at one end by pivot 124 (see Fig. 1) to the overhanging arm C, extending rearwardly therefrom and having at its free rear end an elongated slot 125, which is entered and occupied by a stud 126 at the working end of the stop-lever 117. Depending from and pivoted by pivot 127 to lever 123, near the middle thereof, is a vertical rod 128, which extends downwardly through a guide-aperture in the bed-plate to below the bed-plate. This rod 128 has a catch shoulder or lip 129, formed by a collar 130 on the rod 128 or otherwise, the collar being in effect simply a diametrically-enlarged portion of the rod. Coöperating with the catch-lip 129 is a horizontally-extending rod 131, extending through guide-apertures in the standard B and pivotally connected by

pivot 132 to the middle part of the trip-lever 100. The rod 131 is normally held by a spring 133 with its free end engaging the lip 129, at 70 which time also, by the connection between rod 131 and trip-lever 100, the nose 99 of the trip-lever is maintained in the path of the tripping-tappet 98 on the disk 41. The spring 133 tends to move the rod 131 in the direction 75 of the arrow 134; but its movement is limited in that direction by its free end encountering the body of the rod 128. When the lip 129 is thus engaged by the catch-rod 131, the working end of the lever 117 is held away from the 80 drum 102 with its nose 119 and tappet 120 entirely out of the paths of the notch 114, stop 115, and cam-rise 112. When, however, the stitching of the buttonhole is completed, immediately after the knife has performed its 85 operative excursion, the tappet 98 encounters the nose 99 on the trip-lever 100, moving said trip-lever in the direction of arrow 135, (see Fig. 2,) thereby moving the catch-rod 131 (against the resistance of its spring 133) out 90 of engagement with the lip 129, whereby the connecting-rod 128, lever 123, and stop-lever 117 are left free to the action of the spring 121, which thereupon moves the stop-lever into operative relation with the drum 102. 95 The stop-motion mechanism is so timed that after the tripping occurs the shaft E rotates far enough before stopping to carry the tappet 98 beyond and out of the way of the nose 99, so that the stopping mechanism can be 100 readily restored to its normal inoperative position.

When the stopping has been effected, the stop-lever 117 is maintained in locking position by the spring 121 and in restorative position by the free end of the catch-rod 131 resting against the raised portion 130 of the connecting-rod 128.

To again set the machine in motion, it is necessary simply to depress the connecting-rod 128 so that its lip 129 comes below the free end of the catch-rod 131, which thereupon, under the action of the spring 133, moves out above the lip 129 and so holds the rod 128 depressed. The depression of the 110 rod 128 swings the working end of the stop-lever 117 downward against the tension of spring 121, thereby permitting the pawl 104 to resume its active position in the path of the stud 103 on the drive-pulley F. The 120 restoring movement of the catch-rod 131 also restores the nose 99 into the path of the tappet 98.

The connecting-rod 128 can be conveniently depressed by connecting its end beneath the 125 bed-plate A to a treadle, so that the hands of the operator are left free to manipulate the work.

At any time desired, or in case of any emergency, the machine can be stopped at will by 130 simply pulling upon the finger-pull 136, attached to the trip-lever 100.

A special relation between the coacting faces 200 and 201 of the clutch members 104 and 103

requires mention. If these faces were in a radial plane intersecting the axis of the shaft E, the stop-motion would not work properly, since with such an arrangement in order that 5 the pawl 104 might swing into the recess 106 out of the way of the stud 103 it would be necessary to move the stud backwardly against the force of the driving power, and if the effective force of this power should be greater 10 than the force of the spring 121 the pawl 104 would not be moved into the recess 106 at all. To obviate this difficulty, the face 200 of the pawl is beveled so as to lie in a plane within 15 (or coincident with) an arc having the center 105 of the pawl, and the face 201 of the stud 103 is correspondingly beveled. As a consequence the pawl 104 swings freely inward when acted upon by the tappet 120 without necessitating any retrogression of the stud 103. 20 *Tension-release.*—After the completion of a buttonhole and after the machine has been stopped the operator opens the work-clamp by depressing the handle V of the clamp rock-frame S, and in order that the tension on the 25 thread may be released to facilitate the shifting of the work to the position for the next buttonhole or for removing the work means are provided for automatically releasing the tension on the needle-thread simultaneously 30 with opening the clamp.

The tension device may be of any of the well-known kinds. There is shown a tension composed of two tension-plates 137, between 35 which the thread passes on the way to the needle and which are loosely strung on a spindle 138. A spring 139 surrounds the spindle and gives the desired tension, the force of the spring being regulated by a nut 140. Interposed between the outer plate 137 and the 40 spring and loosely surrounding the spindle 138 is a tension-lever 141, having at its middle a fulcrum-bar 142, adapted to bear against the bracket D. A releasing-rod 143, extending horizontally through guide-apertures in 45 the bracket D, extends loosely through an aperture in the lower end of the tension-lever 141. The end of the rod 143, which extends through the lever 141, is screw-threaded, and outside of the lever it carries an adjustable 50 stop 144 and jam-nut 145. At its other end the releasing-rod 143 has a strap with an elongated slot 146, which is entered and occupied by a vertically-extending rod 147, fixed to rock-frame S. When, therefore, the rock-frame 55 is swung to open the work-clamp, the releasing-rod 143 is moved to the left in the direction of arrow 148. (See Fig. 31.) Its stop 144 is thereby brought against the lower end of the tension 141, which is thereupon tilted on its 60 fulcrum, whereby the tension-spring 139 is moved out of coöperative relation with the tension-plates 137, and the tension on the thread is hence removed.

The slot 146 is of sufficient length to accommodate the to-and-fro excursion of the rod 147 with the work-carrier. The rod 147 is prevented from tilting on its axis by a

squared guide-pin 149 thereon sliding in the rectangular way 78.

Quick-motion mechanism.—In case a thread 70 should break during the stitching of a buttonhole it is desirable to at once stop the machine and to quickly bring the buttonhole to the point where the thread broke to resume stitching. This is effected by a key 150, having cross-handle 151, said key fitting over a pintle 152, extending upwardly from the stud or boss 60 on which the gear 61 turns. This key has two lugs 153, adapted to engage two upwardly-projecting studs 154 on the gear 61. 80 When the key is in place, by turning it so as to turn the gear 61 forward said gear 61, pinion 54, and disk 41 are turned to any desired extent, thus moving the carrier O to the desired position. During this movement the 85 pawl 36 and detent 40 both slip on the ratchet 37, so that the movement of the carrier O is rendered wholly independent of the needle-stitching mechanism. This key also can be used to bring the carrier to its proper starting position at any time when it may be displaced therefrom.

Adjusting mechanism.—To adjust the length of the buttonhole, it is only necessary to adjust the cam-stud 42 radially on the disk 95 41. The greater the eccentricity of the cam-stud 42 the greater the diameter of the circle it describes, and consequently the greater the length of the buttonhole. To adjust the cam-stud, the disk has fixed on its upper face 100 (see Figs. 16 and 17) a projecting guide 155, having a guide-slot 156, extending radially outward from the center of the disk, said groove having overhanging margins 157. The cam-stud 42 rests on the guide 155 and has 105 downwardly-projecting legs 158, which grasp the guide 155 on both sides, so that the cam-stud is firmly held on the guide. Beneath the margins 157 is a nut 159, and an adjusting-screw 160, passing through an aperture 110 in the cam-stud and the slot 156, taps into the nut 159. By loosening the screw 160 the cam-stud can be slid radially along the guide 155 to any desired position. By then tightening the screw 160 the nut 159 is jammed against 115 the under sides of the margins 157, thereby locking the cam-stud in position.

To adjust the number of stitches to the inch—that is to say, the spaces between adjacent stitches—it is sufficient to govern the 120 rapidity of the feed of the carrier O, and this is governed by adjusting the pivot 29 of the lever Y to and from the shaft E, whereby the extent of movement of its lower end, and hence the feed of the ratchet-wheel 37, is controlled. The lever Y has a rectangular aperture 161, Figs. 14 and 15, in which slides a block 162, having a tailpiece 163, into which taps a screw 164, extending through a slot 165 in the lever Y, whereby the block 162 is 130 clamped in any desired position on the lever. The block 162 has a bearing-sleeve, through which extends the pivot-pin 29. Said pin extends through a vertical slot 166 in the stand-

ard B, and its inner end, which is screw-threaded, taps into a locking-nut 167 inside of the standard. By loosening screw 164 and pin 29 the block 162 can be adjusted to and from the shaft E, thus adjusting the pivot on which lever Y swings, and on tightening the said screw and pin the pivot is maintained in position.

The adjustment of the distance between the two straight sides of the buttonhole-stitching is effected by adjusting the extent of lateral movement of the carrier bottom plate W. The swinging plate 57 has a curved slot 168, Figs. 19 and 20, concentric with the pivot-pin 169 between the plate W and link 58. The pivot-pin 170, (screw-threaded at its lower end,) between links 58 and plate 57, extends through the slot 168 and is fastened to said plate 57 by a nut 171. By adjusting the pivot-pin 170 in slot 168 its distance from the center of oscillation (the stud 55) of plate 57 is varied, and hence the extent of lateral travel of the work-carrier is adjusted.

The adjustment of the bight of each stitch is effected by varying the extent of lateral oscillation of the needle-bar H, and this is done by adjusting the pivot-pin h of the lever K to and from the auxiliary shaft I. Depending from the bracket D is a bracket 172, having a rectangular opening or slot 173. (See Figs. 8 to 12.) In this slot a bearing-block 174 slides vertically to and from the shaft I. The pivot-pin h rocks in this bearing-block. The pivot-pin has an integral shoulder 175 between it and the lever K, and its squared screw-threaded shank extends through a rectangular slot 176 in the lever K, beyond which it projects sufficiently to receive a clamping-nut 177. By loosening this nut the pivot-pin h and its bearing-block are adjusted and by tightening the nut the lever K is clamped between the shoulder 176 and the nut 177.

To provide for cutting buttonhole-slits of different lengths, the knife 80 is made removable, so that knives of different lengths may be attached to the plate 79. The knife 80 is held in place by a plate 178 and screws 179. (See Fig. 25.)

Several features of the invention I regard as especially important. The lateral vibration of the needle and its use in connection with the simple longitudinal and lateral feed of the work is of special importance, both on account of the simplicity of construction and effectiveness of operation and because the work can be placed straight and without folding in the machine and there is no turning of the work during the stitching operation.

The mode of bringing the cutter into operation by an instantaneous movement is also of especial importance. It thus becomes possible to operate the cutter directly from the needle-bar, thus securing accuracy in cutting the buttonhole-slit and great simplicity in the cutting mechanism.

The stop-motion and the means for converting uniform rotary motion into uniform reciprocal movement are also features of special importance and utility in the machine. 70

The special mention of these features is not to be construed, however, as detracting from the importance of the other features of the invention which have been described.

The machine as a whole is rapid and effective in operation and makes handsome, perfect, and strong buttonholes, and it is simple in construction, considering its capabilities, and is not liable to get out of order. 75

Many of the details of the machine can be altered and modified without departing from the spirit of the invention, and the specific embodiment of the invention illustrated and described is to be considered simply as illustrative of the invention and as exhibiting 80 what I consider at present as the best embodiment of the invention when applied to a Standard sewing-machine.

The bed-plate A has a special plate in which the eye d and slit 81 are located. This plate 90 consists of two parts 202 202, adjustably attached to the bed-plate, so as to be movable to and from each other, their contiguous edges constituting the opposite margins of the slit 81. (See Figs. 2 and 6.) In case through 95 use the margins of the slit 81 become worn, dull, or ragged the plates 202 202 can be removed, ground down properly, and replaced, thus insuring the proper cutting of the buttonhole-slit. 100

I claim as my invention—

1. The work-carrier comprising a bottom laterally-moving plate and an upper slide movable lengthwise on the bottom plate, the step-by-step revolving cam-stud having a 105 rounded triangular outline, and a slotted yoke operatively connected with said work-carrier slide, in the slot of which yoke said cam-stud enters, in combination with a rotating cam moving in unison with said cam-stud, said cam having two long dwells of different radii connected by abrupt rises, and a movable slotted plate in the slot of which said cam enters, said slotted plate being operatively connected with said carrier-plate, substantially 110 115 as set forth.

2. The work-carrier comprising a laterally-movable bottom plate and an upper slide movable lengthwise on said bottom plate, the rotating toothed disk having a step-by-step rotation, the triangular cam-stud eccentrically located on said disk, and the rectilinearly-reciprocating slotted yoke operatively connected with said slide in the slot of which said cam-stud enters, in combination with the 120 125 idle-pinion engaging said toothed disk, the swinging slotted plate swinging on the same axis as that of said idle-pinion, said slotted plate being operatively connected with said work-carrier bottom plate, and a gear engaging said idle-pinion and having a cam entering the slot of said swinging slotted plate, 130

said cam having two dwells of different radii united by abrupt rises, substantially as set forth.

3. The driving-pulley, the stud thereon, the driven drum having a recess and a notch therein, a pawl pivoted to said drum and occupying said recess, a spring holding said pawl outward in the path of said stud, said pawl having a cam-incline then exterior to the periphery of said drum out of the path of said stud, in combination with a movable nose and tappet always out of the path of said stud and normally out of the paths of said notch and cam-incline, and means for moving said nose into the path of said notch and said tappet into the path of said cam-incline, substantially as set forth.

4. The driving-pulley, the stud thereon, the driven drum having a recess and a notch therein and a projecting stop alongside of said notch, a pawl pivoted to said drum and occupying said recess, and a spring normally holding said pawl beyond the periphery of said drum and in the path of said stud, said pawl having a cam-incline then exterior to the periphery of said drum but out of the path of said stud, in combination with a movable nose and tappet normally held out of the paths of said notch, stop, and cam-incline, and means for releasing said nose and tappet, and a spring for bringing said nose into the path of said stud and notch and said tappet into the path of said cam-incline, substantially as set forth.

5. The drum, and the movable pawl, in combination with the slotted link, and pin, for limiting the movement of said pawl, substantially as set forth.

6. The main shaft E, drive-pulley F, drum 102 with notch 114, stud 103, and pawl 104, lever 117, with nose 119 and tappet 120, spring 121, lever 123, and connecting-rod 128 with catch 129, in combination with the rotating disk 41 with stop-tappet 98, trip-lever 100 with nose 99, catch-rod 131, and spring 133, substantially as set forth.

7. The main shaft E, drive-pulley F, drum 102 with notch 114, stud 103 and pawl 104, lever 117 with nose 119 and tappet 120, spring 121, lever 123, and connecting-rod 128 with catch 129 and enlargement 130, in combination with the rotating disk 41 with stop-tap-

pet 98, trip-lever 100 with nose 99, catch-rod 131, and spring 133, substantially as set forth.

8. For adjusting the number of stitches to 55 the inch, the operating-lever of the feeding mechanism having two slots 161, and 165, the block 162 adjustable in said slot 161, said block having a tailpiece 163 overlapping said slot 165, a set-screw passing through said slot 60 165 and tapping into said tailpiece, in combination with an adjustable pivot-pin upon which said block 162 turns, substantially as set forth.

9. For adjusting the number of stitches to 65 the inch, the operating-lever of the feeding mechanism having two slots 161 and 165, the block 162 adjustable in said slot 161, said block having a tailpiece 163 overlapping said slot 165, a set-screw passing through said slot 70 165 and tapping into said tailpiece, in combination with the standard B, having slot 166, a nut 167 within the standard, and an adjustable pivot-pin screwing into said nut 167, upon which pin said block 162 is journaled, substantially as set forth.

10. The reciprocating work-carrier, the rotating operating-disk 41, having radial guide 155, with radial slot 156, with margins 157, in combination with movable stud 42 having 80 legs 158 straddling said guide 155, the movable nut 159 below said margins, and the screw 160 passing through said stud and slot, and tapping into said nut, substantially as set forth.

11. The vertically-movable cutter-bar 75, spring 76, for elevating the same, carrier 79, at the lower end of the bar 75, cutter 80, on said carrier, and horizontally-swinging tappet 83, pivoted on said carrier and having slot 85, in combination with the bed-plate having slot 87, sliding bar 88, beneath said bed-plate, and vertical rod 86 attached to said bar 88 and extending upwardly through said slots 87 and 85, and means for moving said sliding bar 95 back and forth, substantially as set forth.

In witness whereof I have hereunto signed my name in the presence of two subscribing witnesses.

JULIUS C. GOODWIN.
